UNITED STATES PATENT OFFICE

2,586,200

HOT-AIR DRYER FOR SLASHERS

Gaines L. Ball, West Point, Ga., assignor to Batson-Cook Company, West Point, Ga., a corporation of Georgia

Application May 25, 1950, Serial No. 164,277

10 Claims. (Cl. 34—66)

1

Slashers are used in the textile industry to apply starch or other liquid to yarn preparatory to winding onto a loom beam for weaving. The necessity of a dryer in such an operation is to remove the moisture that is picked up when the starch is applied.

It is an object of the present invention to provide a dryer for slashers which is compact in design and arranged for use with any presently existing head and size box.

Another object of the invention is to provide a dryer for slashers wherein the material to be dried is passed beneath perforated surfaces of several chambers; each chamber being in contact with a blower fan and an air heating unit to provide uniform circulation to the air, as well as uniform drying of the air during its circulating cycle.

A further object of the invention is to provide a dryer of the character described wherein each blower of the unit may be separately controlled or operated simultaneously; and wherein, when the unit ceases operation, one of the blowers continues to operate to remove all hot air from within the various chambers to insure quality in the material itself.

A further object of the invention is to provide a dryer for drying substantially all spun and filament fibers wherein the enclosure or housing of the mechanism is insulated from the interior drying chambers as a means of assisting the initial drying and preventing condensation.

Still another object of the invention is to provide a dryer for slashers wherein a portion of the hot air used for drying is automatically recirculated through a portion of the dryer, thus economizing the use of the heating coils.

Other objects and advantages of the invention will become apparent when viewed together with the accompanying drawing in which:

Fig. 1 is a side view of an embodiment of my invention in a dryer for slashers, the outer housing being removed.

Fig. 2 is a top or plan view thereof.

Fig. 3 is a broken, isometric view showing the heating coils and the interior of the various chambers more clearly.

In the drawings, numeral 10 designates the frame generally which is a fabricated, box-like structure, the sides being extended to form spaced enclosures 11 and 12. The outside walls of these enclosures are provided with openings (not shown) which give access to the various working parts of the machine and which, at the same time, provide somewhat of a cooling cham-

2

ber for the shaft ends, yet still prevent condensation.

Within the framework 10 are separately formed upper, intermediate and lower air chambers 13, 15 and 17, respectively, and upper, intermediate and lower drying chambers 14, 16 and 18, respectively, all arranged in the manner illustrated in Fig. 1. The upper air chamber 13 simply constitutes a sheet metal enclosure 10 the bottom 19 of which is perforated with numerous small holes 19' throughout its length.

The fibers 20, coming from another portion of the machine enter the present dryer at the point designated by the letter E, just below the upper air chamber 13. The material is extended upwardly at an angle and is passed over a roller 21, from whence it is drawn below the perforated bottom 22 of the air chamber 15. It is then passed over a lower roller 23, under the perforated bottom 24 of the chamber 17, over additional rollers 25 and 26 and is finally drawn from the dryer at point Y.

The path of the air through the machine, together with a description of the methods of heating is as follows:

The air is drawn into the dryer just above the point of exit of the material, through an air screen (not shown), and across a heating element 27. The heating element, in this instance, consists of a radiator structure provided with steam coils over which the air passes for heating. The steam element, however, might as easily be replaced by any form of electrical or other heating unit which would serve the same purpose. As shown by the directional arrows, the air enters the lower chamber 18 through a series of dampers 28. These dampers may be manually controlled or may be spring or gravity closed according to the volume and velocity of air passing through. It is also within the scope of the present invention to adjust the damper openings according to the humidity of the air in the various chambers.

From the lower chamber 18, the air is drawn forwardly through another heating coil and into a front pocket or compartment 29.

At the upper end of chamber 17 is a blower 30 rotated by an electric motor 31 mounted on the outer framework 10 of the dryer. The blower 30 has its suction side open to the compartment 29 and its exhaust directed into the chamber 17. Thus far the air is heated twice and is drawn twice across or through the fibers 20. The exhausted air from the blower 30 is forced with considerable pressure into the chamber 17 where

it again is forced through the perforated bottom 24 of the chamber 17 and through the material again and into the bottom chamber 18.

At the rear end of the air chamber 15 is another blower 32 having its suction end open to the rear end of chamber 18 and its exhaust end directed in a manner to exhaust the air into chamber 15.

From the directional arrows it can be seen that much of the air exhausted from chamber 17 into chamber 18 is drawn by the blower 32 and passed over additional heating coils 33, through the perforated bottom of chamber 15, through the material and into the circulating area 16. It will be seen that each time the air is moved from chamber to chamber that it passes through the material to absorb moisture therefrom.

From the area 16 the air is drawn upwardly over the extreme top guide roll 21, around the top of the structure 10 and through additional heating coils 34. The blower 35 is arranged with the suction side open to the air passing through the heating coils 34 and has its exhaust side connected to an opening in the upper chamber 19. When the air is forced through the fibers 20 and the perforated bottom 19 of the upper chamber 13, a portion of it may be allowed to escape to the outer atmosphere through another set of ventilators or dampers 36, while the remainder is drawn through the intake of the blower 32 and re-cycled back through the air chamber 15.

When the dryer ceases operation, the blowers 35 and 32 are cut off, leaving the front blower 30 running. Simultaneously with the cutting off of the blowers 35 and 32, the air dampers 28 are closed to seal off all the hot air in the various chambers, while a set of additional dampers 37 are opened to allow fresh, cool air to by-pass the first heating coil unit 27 and be blown through the machine and exhausted to atmosphere by the blower 30. This system of cooling prevents the fibers from being held too long under high temperatures which has the effect of lessening the quality of the material being processed.

As will be noted from the drawing, three sets of blowers are mounted on three common shafts and operated by individual electric motors. Since the outer ends of all shafts are journaled in the side frame 10, all of the working parts of the machine are easily accessible for repair or replacement.

The machine is compact, easily cleaned and is arranged in such a manner that considerable length of material is dried before it leaves the machine. High inertia loads found in the prior art type of machine using large cylindrical heating drums have resulted in considerable over-ride, causing the material to be sent from the machine undried and in poor condition. In the present invention such over-ride is prevented by the use of small rollers and by leaving a drying blower running after the material ceases to be pulled through the machine.

As pointed out above, the present dryer has the advantage of being able to re-circulate considerable volume of the heated air even after one cycle is completed.

The entire outer shell is intended to be covered with an insulating material 38 to insure uniform heating of the air in the inner chambers and to produce a machine which workmen may operate without subjecting themselves to undue heat commonly caused by this type of prior art textile machinery.

While I have described the invention in detail,

in the embodiment shown in the drawing, it is to be understood that this has been by way of example only, and that changes could be made without departing from the spirit and scope of my invention as defined by the following claims.

I claim:

1. A dryer for slashers comprising an enclosure with means defining an upper drying chamber, an intermediate drying chamber and a lower drying chamber; an upper air chamber adjoining said upper drying chamber and communicating therewith; an intermediate air chamber adjoining said intermediate drying chamber and communicating therewith; a lower air chamber adjoining said lower drying chamber and communicating therewith; means for passing material to be dried through said upper drying chamber, then through said intermediate drying chamber, and then through said lower drying chamber; means for controlling the admission of a gaseous drying medium into said lower drying chamber; a passageway for gaseous drying medium having an intake side communicating with said lower drying chamber and an exhaust side communicating with said lower air chamber; a passageway for gaseous drying medium having an intake side communicating with said lower air chamber and an exhaust side communicating with said intermediate air chamber; a passageway for gaseous drying medium having an intake side communicating with said intermediate drying chamber and an exhaust side communicating with said upper air chamber; heating means positioned in the path of said gaseous drying medium; and means for controlling the exhausting of said drying medium from said dryer.

2. A dryer for slashers comprising an enclosure with means defining an upper drying chamber, an intermediate drying chamber and a lower drying chamber; an upper air chamber positioned adjacent said upper drying chamber and communicating therewith; an intermediate air chamber positioned adjacent said intermediate drying chamber and communicating therewith; a lower air chamber positioned adjacent said lower drying chamber and communicating therewith; means for passing material to be dried through said upper drying chamber, then through said intermediate drying chamber, and then through said lower drying chamber; means for controlling the admission of a gaseous drying medium into said lower drying chamber; first blower means having an intake side communicating with said lower drying chamber and an exhaust side communicating with said lower air chamber; second blower means having an intake side communicating with both said lower drying chamber and said upper drying chamber, and an exhaust side communicating with said intermediate air chamber; other blower means having an intake side communicating with said intermediate drying chamber and an exhaust side communicating with said upper air chamber; heating means positioned in the path of said gaseous drying medium; and means for controlling the exhausting of said drying medium from said dryer.

3. A dryer for slashers comprising an enclosure with means defining an upper drying chamber, an intermediate drying chamber and a lower drying chamber; an upper air chamber positioned adjacent said upper drying chamber and communicating therewith; an intermediate air chamber positioned adjacent said intermediate drying

said lower drying chamber and an exhaust side communicating with said lower air chamber; second blower means having an intake side communicating with both said lower drying chamber and said upper drying chamber, and an exhaust side communicating with said intermediate air chamber; other blower means having an intake side communicating with said intermediate drying chamber and an exhaust side communicating with said upper air chamber; means communicating with said upper drying chamber for controlling the exhausting of said drying medium from said dryer; first heating means positioned in the path of drying medium introduced into said lower drying chamber; second heating means positioned between said lower drying chamber and the intake side of said first blower means; third heating means positioned between the exhaust side of said second blower means and said intermediate air chamber; other heating means positioned between said intermediate

drying chamber and said other blower means; and means for by-passing said means for controlling the admission of a gaseous drying medium so as to admit cooling air to the intake side of said first blower means.
